UNITED STATES PATENT OFFICE.

EDOUARD EUGÈNE DEBONGNIE, OF BERCHEM STE. AGATHE, BELGIUM.

ARCHED ROOF MADE OF UNDULATED SHEET IRON.

Application filed November 30, 1921. Serial No. 518,845.

To all whom it may concern:

Be it known that I, EDOUARD EUGÈNE DEBONGNIE, a subject of the King of Belgium, and resident of Berchem Ste. Agathe, Belgium, have invented certain new and useful Improvements in Arched Roofs Made of Undulated Sheet Iron, of which the following is a specification.

The present invention relates to arched undulated iron roofs; such roofs are very cheap as they do not require any framework, a small number of ties being sufficient for neutralizing the horizontal components of the weight at the supporting points of the roofs. On the other hand, they are absolutely watertight and the differences of temperature do not influence same because the arched roof freely dilates under the action of the variations of temperature.

However, until now, only arched roofs with reduced spans have been constructed. Large spans require stronger sheet iron, which increases the weight, whereby the framework should be reinforced accordingly.

Furthermore no panes can be applied in such roofs, the use of which is thus reduced to buildings not requiring lighting through the roof.

Finally the sustaining columns of such roofs are not connected to each other by rigid stays in a transverse direction, and in order to resist to the wind, these columns and their groundwork should be of large dimensions.

The present invention has for its object a particular construction of such light arched roofs whereby the above mentioned drawbacks are removed and consists in supporting the mediate arched roof portion of reduced span by means of beams in turn supported either by transverse beams or girders or by brackets secured to the columns.

In order to clearly show the nature of the invention, the novel roofing is shown in the accompanying drawing, in which:

Figs. 1 and 2 show two usual arched roofs made of undulated sheet iron, the first one supported on columns, the other on the walls of the building.

Figs. 3 and 4 show one constructive form of the invention, the arched roof being supported upon iron beams or reinforced concrete beams forming parts of girders of the same material and supported in turn upon the columns or walls of the building.

Figs. 5 and 6 show a further constructive form in which the iron or reinforced concrete

beams supporting the arched roof is formed at the end of brackets mounted at either side on the columns or walls.

Fig. 7 shows a third constructive form of the device, the iron beams supporting the arched roof projecting above the girders of which they form a portion.

Fig. 8 shows a fourth constructive form of the invention, the iron beams supporting the arched roof projecting below the girders.

Referring to these drawings, Figs. 1 and 2 show the usual arched roofing 1 made of undulated sheet iron and supported upon columns 3 as shown in Fig. 1, or upon walls 3 as in Fig. 2, according to the usual construction.

In Fig. 3, the arched portion 1¹ of the roof is supported by girders 4, 4, which in turn are supported on or form part of transverse beams 2¹ supported by the columns 3¹ at 5. In Fig. 4, the construction is similar to that of Fig. 3, the columns 3¹ and beams 2¹ and 4¹ being formed of reinforced concrete.

It may be readily seen that the span between the columns or walls 3¹, 3¹ is greatly enlarged, whilst the span of the middle portion covered by the arched roof 1¹ is the same as in Fig. 1 and 2. The lateral portions 5 of the girders 2¹ enable the use of glass 85 panels for lighting the inner of the building.

Figs. 5 and 6 show a constructive form of the invention in which the girders 4¹, 4¹, supporting the arched roof 1² are formed at the end of brackets 6 projecting from the 90 columns or walls 3².

In the constructive form shown in Fig. 7 the beam 4² carrying the arched roof is supported on transverse beams or ties 2² carried on the columns or walls 3³ and said beams 95 project upwardly above the ties 2².

In the constructive form illustrated in Fig. 8, the beams 4³ projects below the ties 2².

It may be readily understood that in these various constructive forms the arched roof of very reduced weight and of low cost is supported on intermediate parts, whereby the span of the building may be considerably enlarged and at the same time panes may be applied all over the lateral parts 105 of the roof at either side of the arched part.

The beams 4, 4¹, 4² or 4³ may be considered as main beams and have a section sufficiently great as to cover, without intermediate supports, the whole width of the building. The columns being eliminated, the girders 2 or 2¹ or 2² and the glass panels

would be supported by means of the beams 4, 4¹, 4² or 4³.

In Fig. 7 the projecting portion of beams 4² projecting above girder 2 may be provided with window blinds or glass panes.

The beams, girders and the like elements of the above construction may be made of any convenient material such as iron, reinforced concrete, wood and the like.

10 Having now fully described my said invention, what I claim and desire to secure by Letters Patent is:

An improved arched roof, comprising a narrow arched roof portion made of undulated sheet metal covering the middle portion of the roof of the building, longitudinal

beams or trusses supporting the edges of said roof portion, and transverse girders or brackets supporting said longitudinal beams or trusses, said transverse girders or brackets being designed to rest on columns or walls of materially greater span than that of the arched roof, whereby to provide space on each side of the arched roof for lighting purposes.

25 In testimony whereof I have hereunto set my hand in presence of two witnesses.

EDOUARD EUGÈNE DEBONGNIE.
